UNITED STATES PATENT OFFICE.

CHARLES SCHLEY, OF GARFIELD, NEW JERSEY.

CIGAR-PERFORATING DEVICE.

Application filed April 21, 1921. Serial No. 463,100.

To all whom it may concern:

Be it known that I, CHARLES SCHLEY, a citizen of Czechoslovakia, and a resident of Garfield, in the county of Bergen and State 5 of New Jersey, have invented a new and Improved Cigar-Perforating Device, of which the following is a full, clear, and exact description.

This invention relates to a perforating device which is particularly designed for cutting a perforation in the end of a cigar, in lieu of cutting or biting the end therefrom as is now the common practice.

The invention contemplates for one of its 10 objects the production of a simple and effective device for perforating the end of a cigar whereby the smoker will obtain a more perfect draft in smoking the same, thus insuring an even burning of the lighted 15 end.

The invention further contemplates the provision of a machine of the character described which includes a movable drill, means for supporting the cigar end in the 20 path of movement of the drill, and means for actuating the drill whereby the same will reach a maximum speed prior to its contact with the cigar end in order to insure an even perforation of the cigar and prevent tearing or fracture of the wrapper. 25

Another object in view resides in the provision of a device of the character described which includes means for regulating the 30 depth of the perforation.

A further object of the invention resides in the provision of a cigar perforating device which is comparatively simple in construction, inexpensive to manufacture, and one which is strong, durable and effective. 35

With the above recited and other objects in view, the invention resides in the novel construction, combination and arrangements of parts as set forth in the following specification, pointed out in the appended claims, and illustrated in the accompanying drawings, it being understood that the right is reserved to other embodiments than those herein illustrated, to the full extent indicated by the general meaning of the terms 40 in which the claims are expressed and by variations in the phraseology of the same.

In the drawing—

Figure 1 is a side elevation of the device with the housing or casing therefor shown 45 in section.

Fig. 2 is a sectional view taken approximately on the line 2—2 of Fig. 1.

Fig. 3 is a sectional view taken approximately on the line 3—3 of Fig. 1.

Fig. 4 is a horizontal sectional view taken approximately on the line 4—4 of Fig. 1.

Referring to the drawings by characters of reference, 10 designates the frame of the machine which is enclosed by a housing 11 having a removable top or cover 12. An 65 electric motor 13 is mounted within the frame and the motor shaft 14 thereof extends through one side of the frame and has keyed thereon a beveled pinion 15 which meshes with a beveled gear 16 arranged in 70 the bracket 17 of the frame. A vertically movable shaft 18 extends through the bearing bracket 17 and the same is provided with a longitudinal keyway 19 which receives the key 20 of the gear 16 whereby said shaft 75 will be rotated by the gear 16, but is capable of independent axial movement with respect thereto. The upper end of the shaft 18 is provided with a concentric axial recess 21 for the reception of the shank of a drill 80 bit 22 which is secured therein against relative rotation and displacement by the retaining screw 23. The top or cover 12 of the housing is provided with an upstanding boss 24 provided with a depending cup 25 85 having a central aperture 26 disposed in alignment with the drill bit 22. The cup 25 is designed to receive and support the cigar end in the path of movement of the drill bit when the shaft 18 is elevated. 90

The mechanism for elevating the shaft 18 comprises a rack bar 27 having a vertical slot 28 through which the stationary and adjustable bolts 29 and 30 are passed. The bolt 30 is arranged in a slot 31 in the frame 95 with the squared head 32 thereof positioned in the vertical groove 33 on the inner side of the frame. A ferrule 34 is positioned over the shank of the bolt 30 exteriorly of the frame, said ferrule being of a length 100 slightly greater than the thickness of the rack bar 27. A binding nut 35 is engaged over the outer threaded end of the shank 30 and serves to frictionally retain the adjustable bolt 30 in its vertically adjusted positions. By this arrangement the bolt 30 which coacts with the lower extremity of the slot 28 is capable of vertical adjustments to provide a vertical adjustable stop for limiting the upward movement of the rack 110.

bar. The bolt 29 provides a stationary stop which coacts with the upper extremity of the slot 28 to limit the downward movement of the rack bar. The lower end of the rack bar 27 is provided with a laterally projecting arm 36, the outer extremity of which is apertured to receive the reduced lower extremity 37 of the shaft 18, a collar 38 being secured thereto to confine said apertured extremity over the reduced end 37 against the shoulder 39 formed at the juncture of the same with the shaft. By this arrangement simultaneous movements between the rack bar and shaft 18 are effected. The means for shifting the rack bar includes a pinion 40 mounted as at 41 on the frame 10 and provided with teeth 42 which mesh with the rack teeth 43 provided on the rack bar 27. A shift rod 44 is mounted on the frame 10 for vertical movements by the engagement of the vertical slot 45 over the guide studs 46 and 47. The shift rod 44 is provided with a laterally projecting fork 48 which operatively engages the eccentrically mounted pin 49 on the pinion 40. The upper extremity of the shift rod 44 extends through an opening 50 in the top or cover 12 and is provided with a head 51. A coiled contractile spring 52 is respectively connected at its opposite ends to the guide stud 46 and the pin 53 carried by the lower extremity of the shift rod to provide means for normally projecting the shift rod upwardly. By this arrangement when the shift rod is forced downwardly against the action of the spring 52 the fork 48 through its engagement with the eccentric pin 49 will rotate the pinion 40 in the direction indicated by the arrow in Fig. 1. This movement of the pinion 40 will move the rack bar 27 upward and at the same time project the shaft 18 upward through the beveled gear 16.

In order to provide means for starting the motor to rotate the drill bit prior to its upward projection, a circuit closing means is provided and is actuated by the initial pressure exerted on the head 51. To accomplish this a switch including a stationary contact member 54 and a pivoted contact member 55 is provided, the former being connected by a conduit wire 56 to one binding post 57 of the motor 13 and the latter being connected by a circuit wire 58 to the source of power. The opposite binding post 59 of the motor is connected by a circuit wire 60 to the source of power. An actuator button 61 is mounted on the head 51 by means of the rods 62 and 63 which extend vertically through openings therein. The rod 63 is operatively connected as at 64 to the free end of the pivoted contact member 55. A coiled expansion spring 65 is disposed between the button 61 and the head 51, the tension of said spring being slightly less than the tension of the spring 52 where-

by pressure exerted on the button 61 will initially compress the spring 65 to throw the pivoted contact member 55 into engagement with the stationary contact member 54 prior to the depression of the shift bar 44 against the action of the spring 52.

In use and operation of the machine the user will insert the cigar end in the cup 25 thereby positioning said end directly in the path of movement of the drill 22. He will then press downwardly on the button 61 moving the same downward against the action of the spring 65 and engaging the contact member 55 with the contact member 54 to energize and start the motor. The starting of the motor will rotate the shaft 18 and drill 22 through the gears 15 and 16. When the button 61 has reached the limit of its downward movement the pressure thus exerted will move the shift bar 44 downwardly against the action of the spring 52, thus rotating the pinion 40 through the fork and pin connection 48 and 49, in the direction indicated by the arrow in Fig. 1. This movement will elevate the rack bar 27, the shaft 18 and the drill 22 to project the same into operative engagement with the cigar end to perforate the same. When the perforating operation has been completed the operator will remove his hand from the button 61 and head 51, thus permitting the springs 52 and 65 to respectively return the shift bar 44 and button 61 to normal position, thereby opening the circuit and retracting the drill from the cigar end.

It will thus be seen that a simple and effective device is provided for perforating the end of a cigar to prepare the same for smoking, said device including means for regulating the depth of the perforation.

Having thus described my invention, what I claim is:

1. A device for preparing a cigar for smoking, comprising a stand, a movable rotary drill mounted on the stand, means for supporting a cigar to dispose its end in the path of movement of the drill, electric driving means for rotating the drill, means for advancing the drill into operative contact with the cigar end, said advancing means being initially operable to actuate the electric driving means prior to the advancement of the drill into contact with the cigar end.

2. A device for preparing a cigar for smoking, comprising a stand, a movable rotary drill mounted on the stand, means for supporting a cigar to dispose its end in the path of movement of the drill, electric driving means for rotating the drill into operative contact with the cigar end, said advancing means being initially operable to actuate the electric driving means prior to the advancement of the drill into contact with the cigar end, and means for returning the drill to

normal position and throwing said driving means out of operation.

3. A device for preparing a cigar for smoking comprising a stand, a movable rotary drill mounted on the stand, means for supporting a cigar to dispose the end to be perforated in the path of movement of the drill, an electric driving means for rotating the drill, means for advancing the drill into operative contact with the cigar end, said advancing means including a circuit closing element which is initially operable to actuate the electric driving means prior to the advancement of the drill into contact with

- 15 the cigar end.
4. A device for preparing a cigar for smoking comprising a stand, a drill mounted therein for sliding movement, means through which the drill is slidable and with 20 which the drill is connected for rotation, means for moving the drill longitudinally through the rotating means, and means for initially rendering the rotating means active prior to the moving of the drill longitudinally.

5. A device for preparing a cigar for smoking comprising a stand, a drill mounted therein for sliding movement, means through which the drill is slidable and with 30 which the drill is connected for rotation, means for moving the drill longitudinally through the rotating means while rotating, means for initially rendering the rotating means active prior to the moving of the drill longitudinally, and means disposed in the path of movement of the drill for supporting the end of the cigar to be perforated in operative relation thereto.

6. A device for preparing a cigar for 40 smoking comprising a stand, a rotary driving means supported thereby, a drill axially slidable through the rotary driving means and connected thereto for rotation therewith, means for supporting the end of a cigar in juxtaposition to and in the path of

movement of the drill, means for moving said drill axially through the rotary driving means while in motion and into contact with the cigar end, and means for actuating the rotary driving means prior to the sliding of the drill whereby the drill will be brought into contact with the cigar while rotating.

7. A device of the character described, comprising a stand, a driving means consisting of a motor, a driving gear on the motor shaft, a driven gear engageable therewith and mounted on the stand for rotation, a longitudinally grooved drill shaft extending through the driven gear, a key carried by the driven gear and coacting with the grooved drill shaft to connect the same thereto for rotation therewith and to permit of sliding movement of the drill shaft through said driven gear, a slotted rack bar 65 swivelly connected to the drill shaft and slidably mounted on the stand, a pinion engageable with the rack bar having an eccentric pin, a shift rod operatively engaging said eccentric pin, a spring for tensioning the shift rod against movement in one direction, a circuit closing member carried by the shift rod, a spring for normally holding said circuit closer open, said latter spring being of lesser strength than the 75 former whereby pressure exerted on the circuit closer to actuate the shift rod initially operates to close the circuit prior to the shifting of the shift rod in order to effect rotation of the drill shaft prior to the shifting of the same into engagement with the article to be perforated.

8. In a cigar perforating device, a drill mounted to slide and rotate, means for rotating the drill, means for sliding the drill 85 during its rotary movement, and means for operating the rotary and sliding means, whereby the rotary means will be operated in advance of the sliding means.

CHARLES SCHLEY.
